UNITED STATES PATENT OFFICE.

HARRY O. RUGH, OF CHICAGO, ILLINOIS, ASSIGNOR TO RAILWAY ELECTRIC MANUFACTURING CO., OF CHICAGO, ILLINOIS.

CIRCUIT-CONTROLLING DEVICE.

1,249,673.

Specification of Letters Patent. Patented Dec. 11, 1917.

Application filed March 23, 1914. Serial No. 826,775.

To all whom it may concern:

Be it known that I, HARRY O. RUGH, a citizen of the United States, residing at Chicago, in the county of Cook and State of Illinois, have invented a certain new and useful Improvement in Circuit-Controlling Devices, of which the following is a full, clear, concise, and exact description, reference being had to the accompanying drawings, forming a part of this specification:

My invention relates to circuit controlling devices and is more particularly available for use on signaling lines although not so limited. My invention has for its object the provision of remotely controlled means for effecting a circuit change and maintaining the change without retaining an operated condition of the controlling portion of the means.

A form in which my invention has found great use, for instance, is in its application to a train despatching system or other conducting system along a right of way when it may be desired to effect certain circuit changes from a central station. More specifically, my invention when so applied, has been used to connect a loud talking transmitter to the conducting system or train despatching system so that the operator at the central station may hear for instance when a train is passing a certain point. This is a very desirable condition to provide for when it is desired by the train despatcher for instance to ascertain whether the train is passing a station where there may be no night operator, or whether a freight train is having difficulty negotiating a heavy grade, finding it necessary to split up the train and take it over the grade in sections. Under such conditions the train despatcher wants to be advised just how soon the track is clear. These grades most usually occur between stations.

Of course, as stated, the invention is not limited to the form above described and other uses are available which will readily suggest themselves. My invention could be further applied for instance in lighting the station lights and extinguishing them, thus to keep the platform illuminated at such times when trains are arriving or departing.

I will describe a form which my invention may take more particularly by referring to the accompanying drawings, in which—

Figure 1 is a front view of a circuit con-

trolling device constructed in accordance with my invention;

Fig. 2 is an end view thereof;

Fig. 3 is a view similar to Fig. 1 showing the device in an alternate position;

Fig. 4 is a diagrammatic view illustrating one form of application of my invention, and

Fig. 5 illustrates another form.

Referring more particularly to Figs. 1, 2 and 3 I provide a base plate 1 having suitable legs 2 by means of which the device may be suitably fastened to a wall or to a containing box. A terminal plate 3 is provided to carry the connecting screws 4 by means of which circuit connection with the various parts of the device is effected. A bracket 5 carries on its upper flat plate 6 the heel plate 7 of a relay 8. This relay has an armature 9 pivotally mounted to the heel plate carrying a spring 10 by means of which through the agency of the adjusting screw 11 the armature is retained in its retracted position of Fig. 1. A limit screw in the form of the adjustable screw 12 confines the rearward movement of the armature. The armature carries a contact spring 13 adapted to effect circuit closure with the terminal 14 whenever the armature is in an attracted position. The armature also carries at its upper extremity a rod or controlling arm 15 pivotally mounted at 16 upon the upper extremity of said armature. This arm 15 controls a pivotally mounted arm 16 pivoted upon the left hand extremity of the horizontal portion 6 of the bracket 5. A spring 17 secured to the arm 16 tends to move said arm against the limit stop 18 mounted upon the heel plate 7. The arm 16 and limit stop 18 are desirably of non-magnetic material. An adjusting screw 19 controls the tension of the spring 17. The arm 16 is confined in its contra-clockwise movement by the adjusting screw 20. The arm 16 also carries a finger 21 slightly resilient but fixedly mounted on said arm 16. The arm 16 also has a projecting pin 22 for purposes presently to appear.

A detent 23 is carried by the spring 24, which spring in turn is fixedly secured to the arm 25. The arm 16 is designed to be moved from the position of Fig. 1 to the position of Fig. 3 when the magnet 8 is momentarily energized. At that time the detent 23 falls in front of the cam-shaped surface of the arm 16 and holds the arm 16

against the stop 20 as shown in Fig. 3. The relay 8, of course, may be deenergized as its continued energization is not necessary to hold the arm 16 in its moved position. In 5 this position of the arm 16 however it will be noted that the right hand extremity of the finger has been raised, thus raising the arm 15 so that the next energization of the relay 8 will cause this arm 15 to press against the 10 detent 23, thereby moving it away from its locking position on top of the arm 16 and permitting the arm 16 in answer to the spring 17 to assume the position of Fig. 1. This is also the result of only a momentary 15 energization of the relay 8 as the armature 9 may be retracted, and it will then fall again into the position shown in Fig. 1.

It will thus be seen that the first energization of the relay 8 moves the arm 16 into one 20 position and a second energization permits it to move into its alternative position, and so on. Each energization of the relay 8 however effects circuit closure between the elements 13 and 14, which continues during the 25 energization of the relay.

The arm 16 is provided with two contact springs 26 and 27 respectively which are fixedly mounted upon an insulating plate 28 carried by this arm. These springs 26 and 30 30 27 are adapted to close contact with springs 29 and 30 whenever the arm 16 occupies the position of Fig. 3. The springs 29 and 30 are mounted upon an insulating bracket 31 fixedly secured to the base plate 1. The pin 35 22 confines the left hand extremity of the arm 15 when the relay is moving the arm 16 from the position shown in Fig. 1 to the position shown in Fig. 3. This is desirable because during this movement the finger 21 40 is being slightly bent so that when the relay is deenergized and the armature 9 retracted, it assumes its normal position to elevate the arm 15 into the position shown in Fig. 3.

A stop 15^a is provided upon the base plate 45 1 to limit the movement of the arm 15. The arm 21 is of course fixedly secured to the element 16 and is capable of a slight spring action to permit of the proper movements of the device as well understood.

Referring more particularly to Fig. 4, I have shown one form in which this particular device may be applied and for purposes of illustration I show here a train despatching system having a central station A, which 50 extends by means of line conductors 32 and 33 to various substations. A step-by-step element 34 may be provided at any point along the right of way which is adapted to close circuit between the arm 35 and the 55 contact spring 36 whenever the proper number of impulses or the proper code has been transmitted over the line circuit by means of the calling mechanism here diagrammatically shown as the key 37. The relay 38 and 60 the slow acting relay 39 in a well known

manner control the element 34 to actuate it in response to impulses so that the circuit between the elements 35 and 36 is closed only as the proper code is received.

It is assumed that this step-by-step element is placed at some point along the right of way, say a heavy grade where it may be desirable for the train despatcher to know whether the trains are experiencing any difficulty in negotiating the grade. To this end a loud talking transmitter 40 is mounted somewhere near the tracks, and this transmitter through the agency of the primary winding 41 and battery 42 may transmit by way of the secondary winding 43 the sounds 80 through the line wires 32 and 33 so that they can be heard in the train despatcher's receiver 44. The train despatcher of course desires to connect this transmitter 40 to the line circuit at certain times and to disconnect it therefrom, but of course does not wish to maintain an operated condition of the step-by-step device or the relay 8 because that would tie up his line. It is for this reason that my device is of special 90 benefit because he can set up the connection of the transmitter to the line wires, and then restore all of the operating apparatus to normal so that his line is clear for other calls or for other business, the line however 95 being in a position to transmit the sounds of an approaching or passing train to his receiver 44 through the agency of the transmitter 40.

Thus whenever the step-by-step device is 100 actuated to close contact between the elements 35 and 36, then the relay 8 is energized to move, through the agency of its armature 9, the springs 26 and 27 into their circuit closing position with the springs 29 and 30. The step-by-step device may then be returned to normal and the relay armature 9 may be returned to normal, but the circuit between the elements 26 and 29 and the elements 27 and 30 is maintained in a 110 closed position. This establishes a circuit from the transmitter 40 through the battery 42, contact spring 29, contact spring 26, primary winding 41, to the receiver 40, and also establishes a circuit from the line wire 115 32 through the conductor 45, condenser 46, secondary winding 43, contact spring 27, contact spring 30, conductor 47, to the line wire 33. Thus any noises along the right of way are transmitted through the agency 120 of the transmitter 40 to the receiver 41. The line 32 and 33 however and selective apparatus connected therewith, as likewise the relay 8, are in their normal unoperated unenergized condition.

Now whenever the train despatcher is 125 through with his investigation and desires to disconnect the transmitter 40, all he needs to do is to again send the code or signal to effect circuit closure between the elements 130

35 and 36, whereupon the relay 8 is again energized to open the circuit between the elements 26 and 29 and the elements 27 and 30 respectively.

5 I have further provided mechanism whereby the train despatcher may be aware of the proper operation of the elements. To this end the armature 9 coöperates with a contact 14 so that a circuit closure between the elements 9 and 14 is effected during the periods of energization of the relay 8. This serves to connect a buzzer 48 in shunt of the transmitter so that when the elements 26 and 29 are also in engagement the buzzer 48 is 10 operated through the agency of a battery 42, thus energizing a primary winding 41 and sending impulses over the line wires through the agency of the secondary winding 43 to thereby apprise the train despatcher that the connection has been established finally between the elements 26 and 29. Of course, when the relay 8 is deenergized the contact at 14 is broken.

Now whenever the train despatcher 25 tends to restore the elements 26 and 27 to normal, the same circuit is initially established at 14 to send the signal, but this immediately ceases when the contact 26 and 29 is broken, thus advising him of a restoration 30 of the connecting elements to normal. Of course, it can be so arranged that the train despatcher gets no signal when disestablishing the system by merely arranging that the springs 26 and 29 shall have their 35 circuit broken prior to the establishment of the contact between elements 9 and 14.

In Fig. 5 I show a further application of my improved mechanism as it may be applied to a station where there is no night 40 operator. A switch 49 is provided to connect the battery 50 through the contacts 35 and 36 to the normal day signal 51, but at night when the operator leaves he reverses this switch to connect the battery 50 and 45 contacts 35 and 36 to the terminals of the relay 8. The relay 8 is then used through the agency of the springs 26 and 27 and springs 29 and 30 to establish connection be-

tween the lamp 52 and the source of supply, here shown as a lighting generator 53. 50 The train despatcher can thus at night time illuminate the platform when trains are arriving or departing.

From what has been stated the nature of my invention will be entirely clear to those 55 skilled in the art. It will also be readily apparent that what is described here for illustrative purposes is not intended to limit the broader nature of the invention.

Having however thus described certain 60 forms in which my invention may be carried out, what I claim as new and desire to secure by Letters Patent is:

1. A circuit controlling device comprising circuit terminals, and a magnet having 65 mechanism whereby successive energizations of said magnet alternately connect and disconnect said circuit terminals, said mechanism including a circuit controlling arm, an independently mounted catch, an armature having means adapted alternately to engage said arm and said catch, and resilient means carried by said arm to shift said means from one to the other of its respective arm or catch engaging positions. 70

2. A circuit controlling device comprising circuit terminals, and a magnet having 75 mechanism whereby successive energizations of said magnet alternately connect and disconnect said circuit terminals, said mechanism including a circuit controlling arm, an independently mounted catch, an armature having a pivoted finger adapted alternately to engage said arm and said catch, and resilient means carried by said arm to 80 shift said pivoted finger from one to the other of its respective arm or catch engaging positions.

In witness whereof, I hereunto subscribe my name this 16th day of March, A. D., 90 1914.

HARRY O. RUGH.
